UNITED STATES PATENT OFFICE.

JAMES A. CAMERON, OF BROOKLYN, NEW YORK.

PICTURE-EXHIBITING APPARATUS.

1,262,578.

Specification of Letters Patent. Patented Apr. 9, 1918.

Application filed February 27, 1915. Serial No. 10,910.

To all whom it may concern:

Be it known that I, JAMES A. CAMERON, a citizen of the United States, and a resident of the borough of Brooklyn, in the county of Kings, city and State of New York, have invented certain new and useful Improvements in Picture-Exhibiting Apparatus, of which the following is a specification.

The present invention relates generally to picture exhibiting devices and has more particularly reference to what is commonly called a stereopticon.

In the prior art of stereopticons it has been customary to exhibit the successive views by means of slides inserted in the machine one after the other, and so far as applicant is aware no attempt has ever been made to exhibit at irregular intervals at the will of the operator successively a series of still-life stereopticon views by means of a continuous carrier having a series of varying and arbitrary images.

The object of this invention is to overcome the slow and cumbersome method previously existing in exhibiting stereopticon views by means of slides, and to this end the invention consists in a continuous carrier having a series of varying and arbitrary images, together with means for exhibiting said images successively as a series of still-life stereopticon views at irregular intervals at the will of the operator.

Other features of construction, combination of parts and arrangements of elements will appear as the specification proceeds.

In the accompanying drawings the invention is disclosed in a concrete and preferred form but changes may of course be made from the construction shown without departing from the legitimate scope of the invention as expressed in the appended claims.

In the said drawings:

Figure 1 is a vertical sectional view through a machine or device embodying the invention.

Fig. 2 is a horizontal transverse sectional view substantially on the line 2-2 of Fig. 1.

Fig. 3 is a vertical sectional view on the line 3-3 of Fig. 1.

Figs. 4 and 5 are detail views of the image carrier.

Similar characters of reference indicate corresponding parts in the different views. 1 indicates an image carrier which may

be of any suitable character and the images of which may be arranged in any suitable way but preferably, as shown in Fig. 3, the images are arranged in two parallel longitudinal series on a regulation film provided with sprocket holes 2 in the usual manner. In this instance, however, there will be four images to each four sprocket holes instead of one picture as it is now generally the custom to have. In this way a greater number of views may be placed on the image carrier so that with a very small roll of film a considerable number of pictures can be obtained.

The images on this carrier, which in the present instance is of a tape-like formation and of a translucent character, may be illuminated by means of reflected or transmitted light but in the present instance a transmitted light is utilized.

As shown, the image carrier is passed over the sprocket wheel 3, thence past the exposure opening 4 between the face plate 5 and the tension means 6, after which it passes over the second sprocket 7 and thence over guide roller 8 and out of the machine. The sprocket 7 is provided with a knurled handle 9 which is turned by the operator the requisite distance to exhibit each picture successively. In order to properly register each picture as it is exposed to the exposure opening 4 the sprocket 7 is provided with a member 10 having notches 11 in its surface, the distance between successive notches being equal to the distance required to bring a new picture in front of the exposure opening. In conjunction with this a latch 12 is provided which rides on the periphery of the member 10 and which is spring-pressed and upon the rotation of the sprocket is lifted out of engagement with its notch and automatically seats itself again in the next notch when the image carrier has been advanced the proper distance. It will be understood that the operator can turn the handle 9 to suit his own convenience and to successively bring a picture in front of the exposure opening and that such picture can remain there any length of time desired by the operator, so that the effect produced is one of a still-life picture or stereopticon view.

The images carried by the carrier are varying and arbitrary, that is to say, if a series of these pictures should be exhibited in rapid succession no motion picture effect

would be produced since each picture would necessarily be distinct and different from the next picture. This of course does not mean that the pictures are entirely unrelated, al- 5 though they may be so.

13 indicates a stereopticon lens and 14 indicates an electric lamp for illuminating the picture. In order to conceal the image carrier during the period of transition from 10 one picture to the next, or to produce a period of obscuration, a mechanically operated shutter may be utilized. In the present instance, however, the circuit 15 and source of current 16 of the electric light is connected 15 to the latch 12 and to the rotatable member 10, the connection to the latter being by means of the brush 17. The rotatable member 10 is provided with alternate insulated and uninsulated portions 18 and 19 so ar- 20 ranged that upon the rotation of the rotatable member the latch 12 which forms one terminal of the circuit engages the insulated portion 18, thereby breaking the circuit through the lamp, and when it drops into 25 the next notch 11 it again makes contact and reestablishes the circuit so that the lamp is lighted again. If the images should be out of register with the exposure opening 4 they may be framed by loosening the 30 nut 20 and by turning the rotatable member 10 slightly the picture can be brought into register without displacing the relative circumferential relation between the said rotatable member and the latch. This move- 35 ment is permitted by means of the slot 21 on the said latch. After register is obtained the screw 20 is again tightened and the device may be operated as before.

In the present construction the sprocket 40 3 also carries a rotatable member 10 of the same construction as the one just described and in connection with which there is also provided a latch 12 which performs the same function as the latch 12 previously de- 45 scribed. The member 10 and the latch 12 adjacent to the sprocket 3 are likewise included in the electric circuit 15 controlling the lamp, as shown. When an image carrier has been passed through the machine in 50 one direction by the rotation of the sprocket 7 it may be run back again in the opposite direction through the machine by rotating the sprocket 3. In order to carry this out properly the cams 22 and 23 are provided 55 by means of which the members 10 and 12 may be disengaged. In Fig. 1, where the sprocket 7 is intended to be operated, the cam 23 has been moved into position to raise the latch 12 out of engagement with the 60 member, but if it is desired to run the film in the opposite direction this cam 23 will be lowered and the cam 22 will be elevated. The means for passing the image carrier through the machine in opposite directions 65 permits the use of an image carrier having

two parallel longitudinal series of images, as shown, one series being shown while the image carrier is moved in one direction and the other series is shown when the image carrier is moved in the opposite direction. 70 To this end the exposure opening 4 is made of the size indicated in Fig. 3 so that only one half of the film is being exposed. When it is desired to expose the other half of the film the bracket 24 which is mounted slid- 75 ingly on the framework 25 by means of the slots 26 and screws 27 is moved sidewise or transversely of the machine. Attached to this bracket 24 is the slide 28 which by its lateral motion brings the exposure opening 80 4 in front of the other series of images and covers the first series of images. The lens 13 and the lamp 14 are likewise secured to this bracket 24 so that simultaneously with the movement of the slide 28 these instru- 85 mentalities are likewise shifted so as to bring them into focus with the section of the film to be exposed. Of course if it is desired to have larger pictures the image carrier indicated in Fig. 4 may be used, in 90 which it will be seen the two parallel series of images are still retained but are of twice the length of those shown in Fig. 3, or if it is desired merely to run the film through the machine in one direction a full size pic- 95 ture such as shown in Fig. 5 may be utilized.

What is claimed, is:

1. A stereopticon comprising a continuous carrier having a series of varying and arbitrary images, means including a sprocket 100 engaging the sprocket holes in the carrier for exhibiting said images successively as a series of still-life stereopticon views at irregular intervals at the will of the operator, means for locking the carrier to hold 105 the images in exhibiting position, and means for preventing the operation of the locking means.

2. A stereopticon comprising a tape-like carrier provided with sprocket holes and 110 having a series of varying and arbitrary images, means including a sprocket engaging the sprocket holes in the carrier for exhibiting said images successively as a series of still-life stereopticon views at irregular 115 intervals at the will of the operator, means for locking the sprocket to hold the images in exhibiting position, and means for preventing the operation of the locking means while a plurality of images are moved 120 through exhibiting position.

3. A stereopticon comprising a continuous carrier having a series of varying and arbitrary images, illuminating means, means for feeding said carrier step by step a pre- 125 determined distance for each step with relatively great intervals of rest between feeding movements to thereby exhibit said images successively as a series of still-life stereopticon views at irregular intervals at 130

the will of the operator, means for locking the carrier to hold the images in exhibiting position, means for moving and holding the locking means out of locking position, and 5 means for rendering the illuminating means inoperative when the locking means is out of locking position.

4. A stereopticon comprising a tape-like carrier provided with sprocket holes and 10 having a series of varying and arbitrary images, illuminating means, means including a sprocket engaging the sprocket holes in the carrier for feeding said carrier step by step a predetermined distance for 15 each step with relatively great intervals of rest between feeding movements to thereby exhibit said images successively as a series of still-life stereopticon views at irregular intervals at the will of the operator, 20 means for locking the sprocket to hold the images in exhibiting position, manually operable means for moving and holding the locking means out of locking position, and automatically operable means for rendering

the illuminating means inoperative when 25 the locking means is out of locking position.

5. In a picture exhibiting device, a means for advancing the image carrier step by step past an exposure opening, a rotatable member having notches in its periphery moving 30 with said means, a latch for engagement with the notches of said rotatable member to indicate when the image carrier has been advanced a predetermined distance, and means for adjusting the latch with respect 35 to the rotatable member so as to permit the latter to shift the image carrier with respect to the exposure opening without disturbing the relation between the notches of the said rotatable member and the said latch. 40

Signed at New York city, in the county of New York and State of New York, this 25th day of February, A. D. 1915.

JAMES A. CAMERON.

Correction in Letters Patent No. 1,262,578.

It is hereby certified that in Letters Patent No. 1,262,578, granted April 9, 1918, upon the application of James A. Cameron, of Brooklyn, New York, for an improvement in "Picture-Exhibiting Apparatus," an error appears in the printed specification requiring correction as follows: Page 2, lines 100-101, claim 1, strike out the words "including a sprocket engaging the sprocket holes in the carrier;" and that the said Letters Patent should be read with this correction therein that the same may conform to the record of the case in the Patent Office.

Signed and sealed this 9th day of July, A. D., 1918.
